(57) **CLAIM**

The ornamental design for a multifunctional folding plier, as shown and described.

DESCRIPTION

FIG. 1 is a front elevation view of a multifunctional folding plier showing the new design;
FIG. 2 is a back elevation view thereof;
FIG. 3 is a left-side view thereof;
FIG. 4 is a right-side view thereof;
FIG. 5 is a top plan view thereof;
FIG. 6 is a bottom plan view thereof;
FIG. 7 is a perspective view thereof;
FIG. 8 is another perspective view thereof;
FIG. 9 is a perspective view of the multifunctional folding plier in a folded position;
FIG. 10 is another perspective view thereof;
FIG. 11 is an enlarged view of the encircled portion in FIG. 7; and,
FIG. 12 is an enlarged view of the encircled portion in FIG. 8.
The dash-dot lines in FIGS. 7, 8, 11, and 12 illustrate the boundaries of the enlarged view indicators and form no part of the claimed design.

1 Claim, 12 Drawing Sheets
